UNITED STATES PATENT OFFICE.

ALEXANDER F. WINTERS AND BASIL R. CRAMPTON, OF GRAND RAPIDS, MICHIGAN.

LATCH.

Application filed January 19, 1925. Serial No. 3,293.

This invention relates to latches of the type adapted to be mounted on swinging doors. One place where the latch is very useful is in connection with refrigerator doors, it being very desirable that a refrigerator door be held tightly shut and that strains upon the door hinges or upon the fastening means employed to attach the latch to the door shall be eliminated as much as possible.

The present invention is concerned with latches of the sliding bolt type. It is a primary object and purpose of the invention to make a latch of this type in which, when the bolt is retracted so as to free the same from its keeper connected to the adjacent door casing or jamb, said bolt will automatically be held in retracted position and stay in such position until the door is again closed. With the closing of the door, means are employed to automatically disassociate the bolt from the latching means which has held it in retracted position, freeing it for outward movement and wedging engagement with the keeper to thereby press the door into tightly closed position. A further object and purpose of the invention is to provide a construction of this character in which a number of the parts entering into the construction of the latch may be made as stampings by use of suitable dies with a great reduction in the cost of manufacture. Various other objects and purposes than those specifically enumerated will appear as understanding is had from the following description taken in connection with the accompanying drawings, in which,

Fig. 1 is a section taken through the fragmentary adjacent portions of the door and door jamb, the latch attached to the door also being shown in section and the keeper on the door jamb partly in section.

Fig. 2 is a view similar to Fig. 1, showing the bolt retracted and the door in the act of moving to closed position.

Fig. 3 is a transverse section through the latch, the plane of the section being substantially at the pivot of the latch handle.

Fig. 4 is an inverted perspective view of an element which is located within the latch housing and which carries the latch bolt.

Fig. 5 is an inverted perspective view of the latch bolt.

Fig. 6 is an inverted perspective of a number to which the latch handle is pivotally connected.

Fig. 7 is an inverted perspective of the latch housing.

Fig. 8 is an inverted perspective of the latch handle, and

Fig. 9 is a perspective view of the pivot used to pivotally connect the latch handle to the members shown in Fig. 6.

Like reference characters refer to like parts in the different figures of the drawings.

The door 1 may be of any suitable construction and is adapted to close a door opening surrounded by the door casing, one side of which is indicated at 2. It is understood that, in refrigerators, the door is hingedly mounted at one vertical edge and a latch is mounted adjacent the opposite free vertical edge of the door. The latch is adapted to engage with the keeper which is mounted on the door casing or jamb 2 in a position to cooperate with the latch bolt.

In the construction of the latch which is attached to the door, a latch housing of sheet metal, preferably, is used having a raised portion which includes a top 3 with inwardly extending parallel sides 4 turned outwardly at their inner edges and formed into attaching flanges 5, through which screws may pass through suitable openings to permanently connect the housing to the door. The housing is also provided with ends 6 and 7 integral with the remainder of said housing, a rectangular or substantially square opening 9 being made through the end 7, and a circular opening 8 through the end 6, as best shown in Fig. 7. At one end, or near said opening 9 a portion of the top 3 is pressed outwardly somewhat, as indicated at 10, through which a somewhat elongated rectangular opening 11 is made, at each side of which an elongated slot 12 of substantially the same length as the opening 11 is cut.

Within the housing made as thus described, a member made of sheet metal is adapted to be located, the same consisting of

a base 13 with an elongated opening 14 therethrough of the same size as the opening 11 before described. Two ears 15 extend at right angles from the base 13, one at each side edge thereof. These ears pass through the slots 12 and the base 13 seats in the recess made by elevating the section 10 at one end of the top 3 of the housing, the openings 11 and 14 coming into direct conjunction and aligning with each other. A handle, 16, preferably cast as one piece is provided, between its ends being formed with projecting bosses 17 from which a downwardly and inwardly extending finger 18 projects. The bosses pass between the outwardly projecting ears 15 which extend beyond the top 3 of the housing, and the finger 18 extends inwardly through the openings 11 and 14, the handle 16 lying above and in a plane paralleling the length of the housing, as shown in Fig. 1. A pivot pin 19 passes through suitable openings in the ears 15 and the lever 16 which opening in the lever 16 is made through said bosses 17. The pivot pin may be of any suitable character. It is shown as including a pin threaded at one end to receive a nut, but it is evident that the threaded end and nut may be replaced by forming a riveted head if desired.

30 A further element used in the construction of the latch, shown in Fig. 4, is made from a single piece of sheet metal, including an elongated base 20 which, at one end, has a section 21 struck therefrom so that the inner edge of the section 21 is raised above the adjacent edge of the base 20. The outer end of section 21 is reduced somewhat in width leaving a short projecting portion 21^a. Sides 22 are turned outwardly at right angles from a portion of the base 20 and the section 21, being spaced apart so as to pass between but lie against opposite sides 4 of the latch housing. These sides 22 extend only a portion of the length of this member, 45 the member for the remainder of its length being formed with outwardly extending wings 23 which, when the member is put in the latch housing, bear against the inner sides of the parts 5 of the housing. At the end 50 opposite where the section 21 is located, an end piece 24 is turned at right angles through which a circular opening 25 is made, the same being adapted to align with the opening 8 made in the end 6 of the latch housing. This member when placed within the latch housing has the end projection 21^a received in the rectangular opening 9, and the end 24 parallels the end 6 of the latch housing.

55 The latch bolt includes a body 26 rectangular in cross section which, at one end, indicated at 27, is cut at an angle as shown. A cylindrical rod 28 integrally cast with the latch bolt extends from the end 27, being adapted to pass through the circular open-

ings 25 and 8 before described, while the body of the bolt passes through the rectangular opening 9 in the end 7 of the housing. An opening 29 is made through the body of the latch bolt into which finger 18 of the handle extends, as shown in Figs. 1 and 2. That portion of the bolt which projects outwardly from the housing when the bolt is in its outer position is indicated at 30 and is somewhat reduced in thickness by cutting away a portion thereof at its inner side, a shoulder 31 being thus formed. On its inner side and outwardly from said shoulder a recess 32 is formed in the projecting end 30 of the latch bolt, while at its outer side the bolt is cut at an incline, as shown at 33, the purpose of which will later appear. The bolt is normally moved to outer position by a coiled spring 34 located around the rod 28, being disposed between the part 24 and the inclined end 27 of the body of the bolt (see Fig. 1).

It is evident that with this construction the tendency of the spring is to normally press the inner side of the bolt tightly against the raised section 21 of the sheet metal member previously described, and when the latch handle is operated so as to retract the bolt as soon as shoulder 31 passes back of the inner edge of the part 21, said shoulder drops back of said inner edge of the part 21 and the bolt is securely held against outward movement. This is what occurs when the door is to be opened and the latch lever is turned outwardly to the position shown in Fig. 2.

The keeper 35 secured to the door jamb 2 extends outwardly from the door jamb and is then turned inwardly toward the edge of the door, making the in-turned section 36 which, at its inner side, is inclined as indicated at 37 to cooperate with the inclined outer side 33 at the end of the latch bolt, a wedging action being set up when the bolt, under the pressure of the spring 34, moves outwardly. This wedging action serves to force the door to tightly closed position. The section 36 at its end is turned outwardly, terminating in an outwardly extending horn 38, the inner side of which is inclined as indicated at 39. If, accidentally, the latch bolt should become disengaged from the retaining part 21 and be projected to its outer position, the closing of the door bringing the projecting end of the bolt against said inclined side 39, causes the bolt to move inwardly until it passes by the corner formed by the junction of the sides 37 and 39 on the keeper, whereupon the bolt is free to move outwardly and engage against said side 37 as is evident. This is not the regular action of the latch bolt but shows that no damage will occur if such accidental or inadvertent disengagement of the bolt should occur.

The keeper has a finger 40 formed integrally therewith located a distance from and inwardly of said part 36 of the keeper before described. The finger 40 terminates in an outwardly turned end 41 located so that with the closing of the door, the end of the latch bolt comes against the part 41, as shown in Fig. 2. This causes, due to the momentum of the door 1, the projecting end of the bolt to be moved and shoulder 31 to disengage from the section 21 holding the bolt in retracted position, freeing the bolt for outward movement. The recess 32 in the bolt receives the end of the part 41 and is necessary as otherwise the bolt could not move to engage with the keeper. This clearly appears in Fig. 1.

The construction of latch described is relatively simple, the parts thereof being economically formed while the assembly is exceptionally quick and easy, the parts merely having to be placed together and the pivot pin or rivet 19 passed through the latch bolt and the ears 15. The base 13 of the member which carries said ears 15 is held in position as it bears against the edges of the sides 22 of the member which carries the latch bolt. The bolt carrying member, shown in Fig. 4, is held against disengagement from the housing as the rod 28 passes therethrough and also through the end of the housing and the bolt cannot be moved outwardly so as to disengage the parts until handle 16 has been removed. By reason of the bolt being held in retracted position when the door is closed strains on the door hinges or on the screw fastenings, which attach the housing to the door, are wholly eliminated. This is a very desirable feature in connection with refrigerators. The construction of latch is very practical and effective as has been proved in tests. The invention is defined in the appended claims and is to be considered as comprehensive of all forms of structure coming within their scope.

We claim:

1. In a latch, a housing having its outer side at one end provided with a rectangular opening and two slots paralleling and located one at each side of the opening, a member having a base with a rectangular opening therethrough, and two outwardly extending ears located within the housing, said ears passing through said slots and said opening aligning with the opening in the housing, a trough-like member disposed within the housing having a bottom and sides extending at right angles therefrom, said sides lying within the sides of the housing and at their edges bearing against the base of the first mentioned member, a latch bolt slidably mounted between the housing and the trough-like member, spring means normally tending to move the bolt in one di-

rection, and a lever pivotally mounted between the ears of the first mentioned member and having a finger extending downwardly through said openings in the housing and the first member, said bolt also being provided with an opening into which the free end of said finger extends, substantially as described. 70

2. A latch comprising a housing having a top and inwardly extending parallel sides, 75 said top adjacent one end having a rectangular opening cut therethrough and two slots, one at each side of and paralleling the opening, a member comprising a base having a rectangular opening therethrough and two 80 outwardly extending ears located within the housing, said ears extending through said slots and the openings in said base and top of the housing aligning with each other, a trough-like member located within the housing comprising a bottom, two outwardly projecting spaced apart sides and an outwardly extending end, said sides lying against and between the sides of the housing and at their upper edges bear against 85 the base of the first mentioned member, a latch bolt slidably mounted within said trough-like member, said bolt including a rod at one end passing through openings made in the end of the housing and in the 90 out-turned end of the trough-like member, and said bolt between its ends having an opening therethrough, a coiled spring located around said rod between the body of the bolt and out-turned end of the trough- 95 like member, and a manually operable lever pivotally mounted on said ears and having a finger extending through the openings in the top of the housing and the base of the first mentioned member and into the opening 100 in said latch bolt, substantially as described. 105

3. A latch comprising a housing having an elongated top and inwardly extending parallel sides, a trough-like member located within the housing including a bottom and outwardly extending sides, said bottom adjacent one end having a section pressed outwardly in a different plane than the plane of the remainder of the bottom, the sides of said member passing between the sides of the 110 housing, a latch bolt slidably mounted in said trough-like member and projecting at one end through an opening in the end of the housing, spring means normally tending to move the bolt outwardly at said projecting end, said bolt at its inner side being formed with a shoulder adapted to engage back of the edge of said outwardly pressed section of the bottom of the trough-like member when the bolt is moved to retracted 115 position, and manually operable means for moving the bolt to retracted position. 120

4. In a latch, the combination of a housing, a bolt reciprocatingly mounted on said housing and having a catch on its inner side 125 130

engageable when the bolt is retracted, a spring for projecting said bolt, a retracting lever pivotally mounted on said housing and having an arm projecting into said housing into sliding engagement with said bolt, the bolt and arm having coacting cam surfaces acting to swing the bolt laterally to catch engaging position when retracted, and a

strike having a part with which said bolt engages on the closing of the door to disengage the bolt catch. 10

In testimony whereof we affix our signatures.

ALEXANDER F. WINTERS.
